Atty.

UNITED STATES PATENT OFFICE.

JOHN I. GABLE, OF WEST SALEM, OHIO.

STABLE-CLEANING DEVICE.

1,177,695.

Specification of Letters Patent.

Patented Apr. 4, 1916.

Application filed March 27, 1915. Serial No. 17,565.

To all whom it may concern:

Be it known that I, JOHN I. GABLE, a citizen of the United States, residing at West Salem, in the county of Wayne and State of Ohio, have invented a new and useful Stable-Cleaning Device, of which the following is a specification.

My invention relates to apparatus for removing manure from stables, cleaning the latter, and separating the liquid manure in the operation.

Its objects are, first, to provide a simple and inexpensive means for mechanically removing stable manure from the stable quickly and conveniently; second, to provide better means for cleaning stables from manure deposited therein; and third, to provide, in connection with such removing and cleaning device, simple means for separating the liquid portion of such manure from the more solid parts thereof.

It consists mainly of a manure conveyer mounted horizontally in a frame the latter being set in a suitable channel or depression formed in the stable bottom just back of the outer end of the stable floor; means for actuating the conveyer in said frame; means for depositing and receiving the liquid manure in a suitable tank; and means, if desired, for delivering the more solid parts outside of the stable.

My invention is illustrated by the accompanying drawings, in which similar letters of reference indicate like parts.

Referring thereto, Figure 1 is a vertical longitudinal section of a stable cleaner embodying my invention; Fig. 2 is a cross section of Fig. 1 on the dotted line X Y; Fig. 3 is a detail view of section of the frame members A and B on which the conveyer is mounted in Figs. 1 and 2; Fig. 4 is a detail sectional view of a portion of the conveyer, detached.

In the drawings, A, B, constitute the sides and middle portion of the frame which supports therein the horizontally operable conveyer W. The latter is made up of a series of cross slats w w, hinged together at their upper longitudinal edges, and flared inwardly so as to freely buckle around rollers P P mounted in said frame at each end thereof—the faces of said rollers being fitted to register with the under and contacting side of said slats respectively, where-55 by said conveyer is propelled about and by

said rollers horizontally over and along said frame connecting member A, substantially as shown in Fig. 1. Power may be applied to either or both of said rollers, as may be desired. Said frame A B is securely fitted into a suitable trench E just below and opposite the outer ends of the stable floor D, said trench being preferably formed of concrete of sufficient hardness for the purpose. Said middle portion A may be located at any distance from the top of the frame to suit the stable needs, and, for better drainage of the liquid manure which falls thereon, may be somewhat sloped longitudinally in the direction of the arrow d, but its upper surface should be secured in line with the upper surfaces of said end rollers P, so as to form a solid support for the upper slats w, which rest thereon. The slats of said conveyer are preferably hinged together by means of a suitable cable c, secured thereto by staples a, as shown in Fig. 4, but the particular manner of hinging said slats together, or securing said cable is immaterial, provided the former are so hinged as to provide a continuous and even upper surface for animals to step upon in passing in and out of the stalls. Moreover, the edges of said slats are beveled inwardly and downwardly in order to provide better means for scraping the liquid manure along the upper surface of said member A, and so as to buckle or fold and fit around said hexagonal surfaces of the rollers P, as aforesaid.

To provide means for separating and removing the liquid manure, I cut away said middle member A at the proper end thereof, and secure underneath the said end a trough S adapted to receive said liquid manure as it is conveyed thereto by the operation of said conveyer slats upon said member A, in the direction of said arrow d. I further construct a suitable tank R located in such position as to receive the discharge of said trough, as shown in Fig. 2. Said tank may be located at any desired position by means of pipe connections which need not be described. To provide means for carrying away the manure beyond the depositing end of said conveyer, an additional conveyer C may be attached thereto as shown in Fig. 1, and operated in connection with said conveyer in the usual and well known way of operating conveyers for like purposes.

I am aware it is not new to construct

conveyers in a manner somewhat similar, and such I do not broadly claim, but limit myself to the construction shown and described, in connection with the novel means 5 I have provided for separating and carrying off the liquid manure from the more solid parts deposited on the conveyer, and for keeping the manure channel clean and the premises sanitary, as stated in the appended claims.

Having thus fully described my invention, what I claim and desire to secure by Letters Patent is—

1. In a device of the character described, 15 the combination with a channel, a horizontal frame mounted in said channel, actuating rollers at its ends, a horizontal member joining the vertical sides of said frame below the top thereof, said horizontal member 20 cut away at a point intermediate said rollers, a conveyer having transverse slats slidable upon said horizontal member between said rollers, and a slanting trough across said frame under said horizontal

member where cut away, substantially as set 25 forth, and for the purpose specified.

2. In a device of the character described, in combination, a channel, a frame in said channel comprising opposite vertical sides and a horizontal member between said sides 30 below the top thereof, a cut away place across said horizontal member, a conveyer having transverse slats slidable upon said horizontal member, actuating rollers mounted in the ends of said vertical sides, respectively, and a slanting trough secured transversely underneath said horizontal member opposite said cut away place therein, and means for conveying liquids from said trough to a receptacle, substantially as set 35 forth.

In witness whereof, I hereunto set my hand this 24th day of February, A. D. 1915.

JOHN I. GABLE.

In presence of two witnesses:

W. E. FREEMAN,
HIRAM B. SWARTZ.
